UNITED STATES PATENT OFFICE.

FELIX TOBIEN, OF ESSEN, GERMANY, ASSIGNOR TO FRIED. KRUPP AKTIEN-
GESELLSCHAFT, OF ESSEN-ON-THE-RUHR, GERMANY.

OVERLOAD PROTECTIVE SYSTEM.

Application filed April 26, 1922. Serial No. 556,718.

To all whom it may concern:

Be it known that I, FELIX TOBIEN, residing at Essen, Germany, a citizen of the German Republic, have invented a certain new and useful Improvement in Overload Protective Systems, of which the following is a specification.

This invention relates to improvements in overload protective systems for motors which are started by means of a starting resistance.

The invention has for its object to provide an overload protective system of the character stated in which the sensibility of the protective device is made dependent on the starting operation in such a manner that the electric system possesses the lowest sensibility at the beginning of the starting and the highest sensibility at the end of the starting, the sensibility gradually increasing during the starting operation.

According to the invention, this object is attained by subjecting the magnetic circuit of an overload circuit-breaker comprising a main current releasing coil and a holding coil, to the influence of an exciting current the strength of which is always dependent on the resistance value of the cut-in portion of the starting resistance.

In the drawing, two embodiments of the subject matter of the invention are diagrammatically illustrated, Fig. 1 being the first and Fig. 2 the second embodiment.

Referring now to the drawing, the first embodiment will be described first. Placed in the main current line in series with the armature B^2 of a main current motor $B^2 B^3$ which is connected to a source of direct current, are a starter D D^1 on the one hand, and on the other hand the break formed by contact members E and E^1 which are movable with relation to each other, and the main current releasing coil E^2 of an overload circuit-breaker. One, E^1 , of these contact members is under the action of a spring E^5 which tends to hold the circuit-breaker in its closed position while the other contacts, E , are fixed. The overload circuit-breaker further possesses another exciting winding E^3 which is constructed as a high resistance coil and which, together with a series resistance F , is connected in parallel to the section of the main current circuit containing the releasing coil E^2 and the contact members E E^1 of the overload circuit-

breaker, and which is wound in the same sense as the releasing coil E^2 . This second exciting winding E^3 , which serves to hold the opened overload circuit-breaker in its open position, will hereinafter be called holding coil. A third magnet coil E^4 of the overload circuit-breaker is connected to the terminals of the starting resistance D in such a manner that, during the starting operation, a current will flow through it in the direction of the arrow w . As this current is directed oppositely to the currents passing through the coils E^2 and E^3 in the direction of the arrows y and z in the operation of the overload circuit-breaker, the additional magnet coil E^4 will exert an action weakening the magnetic pulling force of the two other magnetic coils. This action will be strongest when the entire starting resistance D is cut in, and it will decrease the more, the more the portion of the starting resistance D , through which the motor current passes, is reduced in the course of the starting operation by moving the starting lever D^1 in the direction of the arrow x .

In order to start the motor $B^2 B^3$, the starting lever D^1 is rotated in the direction of the arrow x . As soon as the lever will come into contact with the starting resistance D , the magnet winding B^3 and the armature B^2 of the motor $B^2 B^3$ will receive a current of moderate strength; the currents passing through the coils E^2 and E^3 in the direction of the arrows y and z , are at first likewise of low strength only, because of the starting resistance D being cut-in. However, the third coil E^4 , which weakens the action of the two other magnet coils, is fully excited. According as the starting lever D^1 is moved on, the strength of current in the main current releasing coil E^2 of the overload circuit-breaker will rise, while it will lower in the counter coil E^4 , so that the motor armature B^2 will start rotating and the sensibility of the overload circuit-breaker with respect to overload will increase the more, the more the motor armature B^2 will approach to its working number of revolutions and, accordingly, to its normal rate of operation. During the starting operation, the overload circuit-breaker will therefore only enter into action at a considerably higher overload than after the starting operation has been terminated, when its magnetic pulling force will con-

siderably increase because of the stopping of the counter-action of the coil E^4 .

If the overload circuit-breaker has opened under the influence of an overload, the 5 strength of current in the holding coil E^3 will rise, under the influence of the rapidly decreasing counter electromotive force of the motor B^2 B^3 , so much as to enable the holding coil E^3 to hold the opened overload circuit-breaker in its cut-out position 10 against the action of the spring E^5 .

After the disturbing cause has been obviated, the circuit-breaker can again be closed by moving the starting lever D^1 back, until 15 it rests no longer on the starting resistance D . The main line containing the motor B^2 B^3 , will thus be interrupted, so that the holding coil E^3 will likewise become currentless and the overload circuit-breaker will 20 close under the action of the spring E^5 .

The described system is especially adapted for use in cases in which, with an overload circuit-breaker already present, an increase of the magnetic pulling force beyond 25 the value determined by the main current releasing coil does not come into question, but in which it is found desirable to reduce the magnetic pulling force during the starting operation for the purpose of reducing 30 the sensibility of the overload circuit-breaker.

In opposition to the system according to Fig. 1, the electric connections of the overload circuit-breaker in the second embodiment of the invention illustrated in Fig. 2, are so that the current coming from the positive pole of the source of current will first pass through the break E E^1 and the series resistance F and only thereafter 40 through the main current releasing coil E^2 and the holding coil E^3 . Besides, the starter D D^1 is placed between the overload circuit-breaker and the motor B^2 B^3 which is a direct current motor. The open end 45 of the starting resistance D is connected by a conductor G containing a resistance G^1 , to the point of connection between the holding coil E^2 and the series resistance F . The strength of the current passing during 50 the starting operation through the holding coil E^2 in the direction of the arrow z , which is opposite to the direction of the current in the releasing coil E^2 (arrow y), will therefore depend on the voltage drop 55 caused in the starting resistance D by the current passing through the same. This voltage drop will be largest when the starting lever D^1 touches the free end of the starting resistance D ; it will become equal 60 to zero when the lever D^1 moved in the

direction of the arrow z , will reach the other end of the starting resistance, and the portion of the starting resistance D put in the armature circuit, is likewise equal to zero. The holding coil E^3 will therefore 65 exert a weakening action on the magnetic pulling force of the overload circuit-breaker during the starting operation, this weakening action being largest at the beginning 70 of the starting operation and smallest at the end of the same. Therefore, the operation of the system shown in Fig. 2 is quite similar to that of the embodiment according to Fig. 1. However, the system according to Fig. 2 possesses over the first 75 embodiment the advantage that no additional magnet winding but only a further resistance is used.

Both the above described overload protective systems possess the advantage that 80 overload circuit-breakers comprising a main current releasing coil and a holding coil can be modified in accordance with the invention without any costly changes.

Claims:

1. In a motor control system, a motor circuit, a starting rheostat, an overload switch having contacts in said circuit, a winding on said switch in said motor circuit, said winding causing said switch to 90 open when energized above a certain value, a spring tending to close said switch, a circuit connected in parallel to said winding and switch contacts and comprising a second winding on said switch, said second winding, when energized, preventing said switch from closing under the action of said spring, and a circuit connected in parallel to said starting rheostat, said circuit comprising a winding on said switch, which winding, when energized, counteracts 95 said first named switch winding, thereby accommodating the sensibility of said switch control to the starting operation of said circuit. 100

2. An electric overload protective system, comprising a main current circuit, a motor, a starting resistance for the motor and an overload circuit-breaker consisting of a switch, a main current releasing coil and a holding coil, the starting resistance being placed between the armature of the motor and the switch of the overload circuit-breaker, and the holding coil being arranged 110 in shunt to the break of the overload circuit-breaker as well as to the starting resistance. 115

The foregoing specification signed at Essen, Germany, this 28th day of March, 1922.

FELIX TOBIEN.
